DEVICE FOR SIMULATING GOLF PUTTING HOLES

Filed Dec. 14, 1949

FIG. 1

UNITED STATES PATENT OFFICE

2,606,028

DEVICE FOR SIMULATING GOLF PUTTING
HOLES

Irving Zion, Lawrence, N. Y.

Application December 14, 1949, Serial No. 132,811

6 Claims. (Cl. 273—36)

1

This invention relates to the game of golf in general, and to devices for playing and practicing golf in particular.

It is an object of the present invention to provide a device of this kind by means of which golf-minded persons of all ages may, indoors or outdoors, play or practice golf, and more especially attempt to sink a golf ball in a hole by driving it with a putter, for instance, over a realistic putting green with its usual terrain irregularities.

It is another object of the present invention to make provisions in a device of this kind for quickly changing the terrain conditions of the putting green thereof in an infinite number of ways, thereby to enable and induce a player to exercise his or her utmost playing skill whenever using the device for playing at golf.

It is another object of the present invention to provide a device of this kind which takes up comparatively little space indoors and is readily portable for alternate indoor or outdoor use, and which is simple, sturdy and inexpensive in construction and readily lends itself to efficient mass production.

The above and other objects, features and advantages of the present invention will be more fully understood from the following description considered in connection with the accompanying illustrative drawings.

In the drawings:

Fig. 1 is a top plan view of a device embodying the present invention;

Fig. 2 is a section taken substantially on the line 2—2 of Fig. 1;

Fig. 3 is a reduced top plan view of a device embodying the present invention in a modified manner; and

Fig. 4 is a section taken on the line 4—4 of Fig. 3.

Referring to the drawings, the reference numeral 10 designates a golf playing or practicing device which comprises, in the present instance, a base 12, a terrain disk 14 which is rotatably supported in the base 12, and an approach 16 to the terrain disk 14. The base 12 may conveniently be in the form of an open ring of L-shaped cross section (Fig. 2), having a cylindrical rim 18 and an inwardly turned bottom flange 20 of which both terminate at 22 and 24 (Fig. 1). Suitably secured, as by spot welding, for instance, to the rim 18 of the base 12 is a ring-shaped support 26 which may conveniently be made from angle iron. Rotatably mounted on the top flange 28 of the support 26 and in the base rim 18 is the terrain disk 14 which is provided substantially in the center thereof with a depression

2

30 that resembles a hole on a golf course. The terrain disk 30 may, at least in its top surface thereof, be formed to resemble the terrain conditions of a putting green on a golf course with its customary surface irregularities. In the present instance, the terrain conditions of a putting green are simulated by an uneven surface layer 32 of any suitable material which most realistically resembles the ground of an actual putting green. Thus, the layer 32 on the top surface of the disk 14 may be made of artificial sod, for instance.

The approach 16 to the terrain disk 14 comprises, in the present instance, a plate which is generally L-shaped in longitudinal section (Fig. 2), to provide a long plate length 40 and a laterally projecting short plate length 42 of which the latter is transversely curved like, and suitably releasably secured at 44 to, that part of the periphery of the ring support 26 which is exposed between the opposite ends 22 and 24 of the base 12. In the present instance, the short plate length of the approach 16 extends to the floor or ground 50 on which the base 12 may rest with its bottom flange 20 (Fig. 2), and the plate length 42 is of such height that in its mounted condition the adjacent end 52 of the long plate length 40 is substantially flush and continuous with the top face of the terrain disk 14. Further, the long plate length 40 of the approach 16 rests, in the mounted condition of the latter, with its other end 54 on the ground or floor 50. The long plate length 40 of the approach 16 thus gradually ascends from the floor or ground 50 to the level of the terrain disk 14 in order to lead onto the latter a golf ball which is driven by a player, with a putter, for instance, somewhere on the floor or ground 50. Preferably, the plate length 40 of the approach 16 is at its opposite sides provided with

35 upwardly projecting flanges or walls 56 and 58, respectively, in order to prevent any driven golf ball from rolling off the sides of the approach 16. Similarly, that part of the base rim 18 which extends above the terrain disk 14 will prevent any golf ball from rolling off the latter, except 45 over the approach 16 toward the player who drove it. Thus, the side flanges 56 and 58 on the approach 16 and the extension of the base rim 18 above the terrain disk 14 act as barriers which permit even unskilled persons to play or practice golf with the instant device, without having to chase after each ball which is driven with such force, or is so misdirected, that it would roll off the terrain disk 14 or the approach 16 if it were not for these barriers. Preferably, the plate length 40 of the approach 16 is, like the terrain

disk 14, formed at least in its top surface thereof to simulate the terrain conditions of a putting green of a golf course. As in the case of the terrain disk 14, the plate length 40 of the approach 16 is, in the present instance, provided with an uneven surface layer 60 of any suitable material which realistically resembles an actual putting green, such as artificial sod, for instance.

In forming the layers 32 and 60 on the terrain disk 14 and approach 16, respectively, in realistic simulation of an actual putting green, the top surfaces 62 and 64 of the layers 32 and 60, respectively, are made uneven or irregular to present to a golf ball the same ridges and depressions *r* and *d*, respectively, which are presented by an actual putting green on a golf course. These ridges and depressions *r* and *d* are, of course, unevenly distributed over the area of the terrain disk 14 so that the latter may offer to a player or players an infinite number of different terrain conditions on being turned into any one of an infinite number of angular positions relative to the approach 16. Thus, by frequently turning the terrain disk 14 into different angular positions, a player is called upon to use his or her utmost playing skill at all times in the endeavor to sink a golf ball in the depression or hole 30. By making the instant provisions for changing the terrain conditions on the disk 14 as often as desired, the instant device will keep the interest of a player or players alive over a long period of time, primarily because it always challenges the skill of, and will never be mastered by, any player or players regardless of how often the device is used. Thus the disk 14 is supported for rotation about a substantially vertical axis coextensive with its own axis and the rotation of said disk about said axis is effective to align different portions of the irregularly formed face 62 with the approach 16.

Fig. 3 shows a modified golf-playing or practicing device 10' which differs from that of Fig. 1 primarily by providing on a modified base 12' a gutter 70 of preferably curved cross-sectional shape of which the open top is substantially flush with, or somewhat below, the surface layer 32' of artificial sod, for instance, on top of the disk 14'. The gutter 70 may be substantially angle-shaped in cross-section (Fig. 4), with its top flange 71 deformed cross-sectionally to form the gutter proper, and with its other flange secured in any suitable manner to the cylindrical rim 18' of the base 12'. The terrain disk 14' may rotatably be mounted on a cross-sectionally U-shaped support 13 which is, in turn, mounted on the base 12' (Fig. 4). The gutter 70 extends in the present instance along the cylindrical rim 18' of the base 12' and laterally merges at its ends 72 and 74 into short gutters 76 and 78, respectively, in the approach 16' which may, but need not necessarily be, inclined the same as the approach 16 in Fig. 1. If the approach 16' is not inclined, but extends horizontally instead, the gutters 76 and 78 preferably extend to the end of the approach 16' and are, furthermore longitudinally inclined with their bottoms downwardly toward the end of the approach 16' in order that a golf ball or balls rolling thereto will roll off the approach 16'. If the approach 16' is inclined, the gutters 76 and 78 therein may, a short distance away from the adjacent ends 72 and 74 of the gutter 70, merge with their bottoms, as at 80 and 82, respectively, into the plane of the approach 16'. The approach 16' is, in the present instance, shown plane, i. e., without an uneven

surface layer of artificial sod, for instance, but such a surface layer may obviously be provided on the approach 16', if so desired. In order that a golf ball or balls rolling into the gutter 70 may roll freely onto the approach 16', the bottom of the gutter 70 is preferably gradually slightly inclined downwardly toward the ends 72 and 74 thereof.

While I have shown and described the preferred embodiment of my invention, it will be understood that various changes may be made in the present invention without departing from the underlying idea or principles of the invention within the scope of the appended claims.

Having thus described my invention, what I claim and desire to secure by Letters Patent, is:

1. A golf-playing device, comprising a disk having a single substantially central depression in imitation of a hole in golf, and having one of its opposite faces irregularly formed to resemble the terrain conditions of a putting green, a low support placeable with its bottom on a floor indoors or the ground outdoors and supporting said disk, with said one face up, for rotation about a substantially vertical axis coextensive with its own axis, and an approach connected to said disk, said approach being placeable on the floor or ground the same as said support and providing a surface extending from the floor or ground at a slight inclination thereto to a part of the periphery of said disk and being substantially flush with said one disk face along said part of the disk periphery, the rotation of said disk about said axis being effective to align different portions of said irregularly formed face with said approach whereby an infinite number of terrain conditions may be simulated.

2. A golf-playing device as set forth in claim 1, in which the top face of said approach surface is also irregularly formed to simulate the terrain conditions of a putting green.

3. A golf-playing device as set forth in claim 1, in which said support has an upwardly projecting cylindrical wall which extends along and above the disk periphery except along said part thereof.

4. A golf-playing device, comprising a generally dish-shaped base having an annular rim and a bottom placeable on a floor indoors or the ground outdoors, an inwardly projecting ring support on said base rim intermediate the top and bottom of the latter, a disk rotatably supported on said ring support and that portion of said base rim which projects upwardly beyond said ring support, said disk having a substantially central depression in imitation of a hole on a golf course, and having its top face formed to resemble the terrain conditions of a putting green, and an approach to said disk, said approach being a plate of the general shape of a long L having a long plate length and a laterally projecting short plate length of which the latter is transversely curved like, and releasably secured to the outside of, a peripheral length of said base rim below said ring support so that the outer end of said long plate length may rest on the floor or ground the same as said base bottom, and said base rim is interrupted along said peripheral length thereof above said approach so that the other end of said long plate length may be substantially flush and continuous with said top face of the disk.

5. A golf-playing device as set forth in claim 4, in which the top face of said long plate length

of the approach is also formed to resemble the terrain conditions of a putting green.

6. A golf-playing device, comprising a disk having a substantially central depression in imitation of a hole in golf, and having one of its opposite faces irregularly formed to resemble the terrain conditions of a putting green, a low support placeable with its bottom on a floor indoors or the ground outdoors and supporting said disk, with said one face up, for rotation about a substantially vertical axis coextensive with its own axis, said support having around a part of the periphery and below said one face of said disk a gutter which is outwardly directed at its opposite ends and the bottom of which is slightly inclined downwardly toward at least one end thereof, said gutter being adapted to lead off the support any ball rolling into said gutter from said irregularly formed face of said disk, and an approach connected to said disk, said approach being placeable on the floor or ground the same as said support and providing a surface extending longitudinally from the floor or ground at a slight inclination thereto to that part of the periphery of said disk which is not surrounded by said gutter, and being substantially flush with said one disk face substantially along the last-

5 mentioned part of the disk periphery, and said approach being at its end adjacent said disk and at its opposite sides provided with short longitudinal gutters, respectively, which align with said gutter ends, respectively, and extend in slightly downwardly inclined fashion away from said gutter ends and merge into said approach surface.
